(57) **CLAIM**

The ornamental design for a headset, as shown and described.

DESCRIPTION

FIG. 1 is a perspective view of a headset according to a new design, wherein the opposite front face of the ear cup is a mirror image of the ear cup;

FIG. 2 is a front view of the headset of FIG. 1;

FIG. 3 is a rear view of the headset of FIG. 1;

FIG. 4 is a left side view of the headset of FIG. 1;

FIG. 5 is a right side view of the headset of FIG. 1;

FIG. 6 is a top plan view of the headset of FIG. 1; and,

FIG. 7 is a bottom plan view of the headset of FIG. 1.

The broken lines form no part of the claimed design.
